UNITED STATES PATENT OFFICE.

ROBERT LEWIS JOHNSON, OF HANLEY, ENGLAND.

DESIGN FOR A COVERED DISH.

SPECIFICATION forming part of Design No. 22,565, dated June 27, 1893.

Application filed May 3, 1893. Serial No. 472,907. Term of patent 7 years.

To all whom it may concern:

Be it known that I, ROBERT LEWIS JOHNSON, of Hanley, Staffordshire, England, have invented a new and original Design for a Covered Dish, of which the following is a full, clear, and exact description.

Reference is to be had to the accompanying drawings forming a part of this specification, in which—

10 Figure 1 is a side elevation of a covered dish showing my design. Fig. 2 is a plan of the dish with the cover removed; and Fig. 3 is a plan view of the cover; these three views being deemed necessary to fully illustrate my 15 design.

The leading features of my design are the overhanging cover and the handles at the ends of the dish. The dish is elongated and provided with a flattened base having scroll-like

ornamentations around it, and the sides of the dish are slightly flattened or faceted so as to produce vertical ribs. At the ends of the dish and at the top edge are outwardly curved handles which are ornamented with leaf-like scrolls, and the dish is surmounted by a cover which fits between the handles and the edge of which overhangs the sides of the dish. The cover is provided with scroll-like ornamentations around its edge, and on its top is a knob which is also provided with scroll-like ornaments of a leafy character.

I claim—

The design for a covered dish, herein shown and described.

ROBERT LEWIS JOHNSON.
